LAMP SHADE HOLDER

David J. Ross, Benton Harbor, Mich.

Application June 9, 1943, Serial No. 490,124

3 Claims. (Cl. 240—108)

This invention relates to improvements in lamp shade holders.

The main objects of this invention are:

First, to provide an improved lamp shade which is capable of ready adaptation to lamps of the type including a lamp socket having an externally threaded portion and which engages the lamp socket in a very secure and effective manner for supporting the shade in the desired position and against tilting movement.

Second, to provide a lamp shade which, while economical to produce, is very attractive in appearance.

Third, to provide a structure which permits the user or the merchant to vary the trimming to meet individual requirements or taste.

Objects pertaining to details and economies of the invention will definitely appear from the description to follow. The invention is defined in the claims.

A structure which embodies the features of my invention is clearly illustrated in the accompanying drawing, in which:

Fig. 1 is a fragmentary side elevation of a lamp embodying the features of my invention, portions being broken away and partially in section on line 1—1 of Fig. 2 to show structural details.

Fig. 2 is an inverted view of the lamp shade and holder partially in horizontal section and partially broken away.

Fig. 3 is an enlarged fragmentary view in vertical section illustrating details of the shade structure.

In the embodiment of my invention illustrated 1 represents a lamp standard which is provided with a socket 2 having an externally threaded portion 3. The lamp bulb 4 is threaded into the socket. The threads 3 commonly result from the forming of the internal threads to receive the lamp. The shade holder element 5 is provided with a central hub portion 6, a rim portion 7 and spider arms 8 connecting the rim portion to the hub portion. The hub portion has a central opening 9 therein of such diameter as to receive the socket of the lamp.

The shade holder 5 is of substantial thickness and is preferably formed of fireproof or fire resistant material, the product commonly known as Masonite being an example of material which I have found satisfactory. The holder is rotatively forced down on the socket with the result that the threads of the socket form threads in the holder opening and a very secure engagement results, one which prevents accidental dis-

engagement and also tilting of the holder on the socket.

The rim 7 is provided with a spaced series of curved recesses or notches 10 adapted to receive the inwardly disposed flutings 11 of the fluted shade 12. These flutings and recesses are preferably so formed that the flutings fit the recesses, thereby preventing shifting movement of the shade on the holder. The inwardly disposed flutings of the shade have pairs of eyelets 13 formed therein adapted to receive the ribbon-like strand 14 which is arranged through the eyelets and below the segmental portions 15 of the rim between the recesses. This effectively retains the shade on the holder and the ribbon or strand may be tightened up so as to clamp the shade on the holder, thus providing a very secure assembly and one in which the shade holder cannot be tilted on the lamp socket or the shade tilted or shifted on the holder without it being subject to distorting stresses.

The shade walls terminate in a cylindrical top portion 16 which has a reinforcing sleeve 17 secured within the same. The ruffle or other ornamental material 18 is secured around this cylindrical portion and the shade illustrated is provided with a ruffled trimming 19 at its lower edge.

The shades and the holders may be packed and shipped in the knockdown and readily assembled by the merchant or the user.

I have illustrated and described an embodiment of the invention which I consider very practical. I have not attempted to illustrate other embodiments or adaptations which I consider desirable, particularly in matters affecting design, as it is believed this disclosure will enable those skilled in the art to embody or adapt my invention as may be desired.

Having thus described my invention what I claim as new and desire to secure by Letters Patent is:

1. The combination of a lamp shade holder of substantially flat fibrous material comprising a central hub portion, a rim portion and a spider portion connecting said hub and rim portion, said hub, rim and spider portions all lying substantially in a plane, said hub portion having a central opening therein adapted to receive a lamp socket having an externally threaded portion and for threading engagement therewith, the fibrous material of said hub portion being of substantial thickness to permit of a substantial engagement of said hub portion over said lamp socket, the rim portion having a plurality of spaced recesses therein, a shade having fluted side walls, the flut-

ings being disposed in said recesses for supporting engagement with said holder, said shade sloping upwardly and inwardly from said rim portion, said shade having openings in its flutes engaged in said recesses and positioned below the shade holder, and a strand threaded through said openings and engaging the lower side of the portions of the holder rim portion between the recesses thereof to retain the shade on the holder.

2. The combination of a lamp shade holder of substantially flat fibrous material comprising a central hub portion, a rim portion and a spider portion connecting said hub portion and rim portion, said hub, rim and spider portions all lying substantially in a plane, said hub portion having a central opening therein adapted to receive a lamp socket, the fibrous material of said hub portion being of substantial thickness to permit of a substantial engagement of said hub portion over said lamp socket, the rim portion having a plurality of uniformly spaced curved recesses therein, a shade having fluted side walls, the flutings fitting into said recesses for sup-

porting engagement with said holder, said shade sloping upwardly and inwardly from said rim portion, said shade having pairs of eyelets in its flutes engaged in said recesses and positioned below the shade holder, and a strand threaded through said eyelets and engaging the lower side of the segmental portions of the holder rim portion between the recesses thereof to retain the shade on the holder.

3. The combination of a lamp shade holder including a rim portion having a plurality of spaced recesses therein, a shade having fluted side walls, the flutings being disposed in said recesses for supporting engagement with said holder, said shade sloping upwardly and inwardly from said rim portion, said shade having openings in its flutes, said openings being positioned adjacent and below the lower side of the shade holder, and a strand threaded through said openings and engaging the lower side of the portions of the holder rim portion between the recesses thereof to retain the shade on the holder.
